(57) **CLAIM**

The ornamental design for a portion of cigar cutting divot repair tool, as shown and described.

DESCRIPTION

FIG. 1 is a front perspective view of a portion of a cigar cutting divot repair tool illustrating our new design;

FIG. 2 is a left side elevation view thereof, the right side elevation view thereof being a mirror image thereof;

FIG. 3 is a front elevation view thereof;

FIG. 4 is a rear elevation view thereof;

FIG. 5 is a bottom plan view thereof; and,

FIG. 6 is a top plan view thereof.

The broken line showing the remainder of the cigar cutting divot repair tool is in the drawings for illustrative purposes only and form no part of the claimed design.
